US00D625205S

(12) **United States Design Patent**
Schermuly

(10) **Patent No.:** **US D625,205 S**
(45) **Date of Patent:** **** Oct. 12, 2010**

(54) **SHOWER TIMER**

(75) Inventor: **Nigel Schermuly**, Stroud (GB)

(73) Assignee: **Bob Products Limited**, Stroud (GB)

(**) Term: **14 Years**

(21) Appl. No.: **29/325,899**

(22) Filed: **Oct. 8, 2008**

(30) **Foreign Application Priority Data**

Apr. 8, 2008 (GB) 4007080

(51) **LOC (9) Cl.** **10-03**

(52) **U.S. Cl.** **D10/44**

(58) **Field of Classification Search** D10/40,
D10/44; 368/93-95

See application file for complete search history.

(57) **CLAIM**

The ornamental design for a shower timer, as shown and described.

DESCRIPTION

FIG. 1 is a top front right side perspective view of a shower timer showing my new design.

FIG. 2 is a front elevational view thereof; and,

FIG. 3 is a right side elevational view thereof, with the left side being a mirror image thereof.

The stippling in FIGS. 1-2 shows certain details of fluid and of fluid levels within the shower timer.

1 Claim, 3 Drawing Sheets

FIG. 1

FIG. 2

FIG. 3
